UNITED STATES PATENT OFFICE.

ALBERT TARBET, OF SAN DIEGO, CALIFORNIA.

SELF-LOCKING MILK-CAN COVER.

Application filed February 21, 1921. Serial No. 446,749.

To all whom it may concern:

Be it known that I, ALBERT TARBET, a citizen of the United States, residing at San Diego, in the county of San Diego and State 5 of California, have invented new and useful Improvements in Self-Locking Milk-Can Covers, of which the following is a specification.

It is the object of this invention to provide 10 means for readily locking the cover of a milk can or the like, the invention comprising an extremely simplified structure including a retaining band adapted to be received around the mouth of the milk can 15 and lock the cover plate for the same with relation to the can.

The invention will be readily understood from the following description of the accompanying drawings, in which—

20 Figure 1 is a perspective view of a milk can provided with the improved locking means.

Fig. 2 is a perspective view of the retaining band forming the locking means.

25 Fig. 3 is a side elevation showing the mouth of a milk can provided with the improved locking means.

Fig. 4 is a top plan view of the same.

Fig. 5 is a vertical section on the line 5—5 30 of Fig. 4.

Fig. 6 is a plan view of the closure cap for the can.

Fig. 7 is a side elevation of the same partly broken away.

35 In the drawings is shown a milk can 1 having a mouth 2 of reduced diameter, although it will be apparent that the improved locking means may be as readily employed in connection with a can having 40 straight sides, so that the mouth of the same is of the same diameter as the can.

A flange is provided at the upper edge 45 of mouth 2 and is preferably formed with an outwardly and downwardly inclined upper surface, as shown at 3, and an inwardly and downwardly inclined lower surface, as shown at 4, so as to form a wedge-shaped flange. The closure cap for the can is shown as a disc 5 having the peripheral portion thereof which is received over the flange upon the mouth of the can inclined downwardly as shown at 6 so as to rest flat against the downwardly inclined portion 3 of the flange. A sealing ring 7 of rubber 50 or the like is preferably positioned between the flange of the can and the closure cap.

A retaining band is employed for holding the closure cap in position with relation to the mouth of the can. This band is shown as a strip 8 having a suitable spring lock 60 mechanism at one end thereof adapted to engage a catch 10 projecting beyond the opposite end of the band. The lock is preferably operated by a suitable key so that the band may be readily locked to form a closed 65 annulus or as readily unlocked to permit the ends of the band being swung apart. The band is received around the flange at the mouth of the can and around the edge of the closure cap for the same. 70

Clips are provided upon the inner surface of the band for engaging the closure cap and the flange. Each of these clips is shown as a substantially U-shaped metallic member 12 riveted at the base of the U to 75 the inner surface of the band, as shown at 13, so that the arms of the U will engage the inclined peripheral portion of the closure cap and the downwardly and inwardly inclined surface 4 of the flange respectively. The 80 spring tension of the clips will thus tend to hold the closure cap to the flange when the retaining band is locked in position. It will thus be seen that an efficient lock is provided for preventing the removal of the 85 closure cap of the can.

Various changes may be made without departing from the spirit of the invention as claimed. 90

What is claimed is:

1. The combination with a milk can having an outwardly projecting flange around its mouth, said flange having an outwardly and downwardly inclined upper face and an inwardly and downwardly inclined lower 95 face and a closure comprising a disc with an outwardly and downwardly inclined rim to fit the flange, of a band, U-shaped resilient members secured to the band, the ends of said U-shaped members being adapted to 100 engage the lower face of the flange and the upper face of the closure, and lock mechanism for securing the ends of the band together.

2. The combination with a milk can, of 105 a wedge-shaped flange extending around the mouth of the can, a cover having a rim to fit the upper face of the flange, a band having U-shaped clips extending inwardly to force the cover against the flange, and means 110 for locking the ends of the band together.

3. In combination, a receptacle having a

flanged mouth, a closure for the mouth, a split band encircling the flange, and resilient clips carried by the band and adapted to be held under tension and in gripping relation with respect to the flange and closure when the band is in circular form about the flange.

4. In combination, a receptacle having a flanged mouth, a closure for the mouth, said 10 mouth and closure being formed with divergent surfaces, spring clips having jaws normally converged and adapted to be diverged when engaging said surfaces for constantly urging the closure to closed position 15 upon the mouth, and means for holding the

clips in engaging position with respect to said surfaces.

5. In combination, a receptacle having a flanged mouth, a closure for the mouth, spring clips having jaws normally contracted and adapted to be expanded to grip the flange and closure for constantly urging the latter to closing position upon the mouth, and a common means for retaining all the clips in proper spaced relation and in urging relation with respect to the flange and closure. 20 25

In testimony whereof I have signed my name to this specification.

ALBERT TARRET.
